United States Patent Office

Des. 186,103
Patented Sept. 15, 1959

186,103

CHAIR

Bela B. Junkunc, Chicago, Ill.

Application May 6, 1959, Serial No. 55,796

Term of patent 14 years

(Cl. D15—1)

Figure 1 is a front elevational view of a chair embodying the invention;

Figure 2 is a side elevational view of the chair shown in Figure 1;

Figure 3 is a top plan view of the chair shown in Figures 1 and 2;

Figure 4 is a rear elevational view of the chair shown in Figures 1, 2 and 3; and

Figure 5 is a bottom plan view of the chair shown in Figures 1, 2, 3, and 4.

I claim:

The ornamental design for a chair, substantially as shown.
